CLAIM

The ornamental design for a stove panel guard, as shown and described.

DESCRIPTION

FIG. 1 is a front perspective view of a stove panel guard showing my new design;

FIG. 2 is a front elevational view thereof;

FIG. 3 is an end elevational view thereof, the opposite end being a mirror image;

FIG. 4 is a top plan view thereof, the bottom view being a mirror image;

FIG. 5 is a rear perspective view thereof; and,

FIG. 6 is a reduced perspective view thereof, the stove shown in broken lines is for illustrative purpose only and forms no part of the claimed design.

FIG. 1.

FIG. 2.

FIG. 4.

FIG. 3.
